UNITED STATES PATENT OFFICE.

WILLIAM H. DAYTON, OF TORRINGTON, CONNECTICUT.

MACHINE FOR SWAGING NEEDLE-BLANKS.

SPECIFICATION forming part of Letters Patent No. 268,874, dated December 12, 1882.

Application filed March 24, 1882. (No model.)

To all whom it may concern:

Be it known that I, WILLIAM H. DAYTON, of Torrington, in the county of Litchfield and State of Connecticut, have invented an Improvement in Machines for Swaging Needle-Blanks and other Cylindrical Articles, of which the following is a specification.

In Letters Patent No. 52,493, granted to Hopson, Brooks, and Manville, the wire to be reduced or pointed is passed in between two jaws that are closed by a toggle motion, and in the Patent No. 58,730, granted to E. J. Manville, a pair of dies and toggles are employed in connection with a ring that supports the toggles.

My present invention is an improvement upon the aforesaid devices, whereby the mechanism is relieved from considerable friction at the same time that its efficiency is promoted and the parts are rendered more durable.

I employ a revolving shaft having across its end a mortise or groove and a pair of sliding dies similar to those in the said Patent No. 58,730, and around the same is a cylindrical shell, and there are rollers between the dies and the shell, said rollers having their axes in ring-bearings, so as to roll around within the shell by the action upon them of the dies, the ends of which dies come into contact with the rollers successively, and the rollers, being at opposite sides within the shell, act as rolling toggles to press the dies together. In this manner there are as many closures of the dies each revolution of the shaft as there are rollers in the circular range, and the parts are constantly in motion, so that there is an extended wearing-surface on the interior of the shell and the exterior of the rollers. Hence the apparatus is very durable, and there is but little friction of the parts.

In the drawings, Figure 1 is a longitudinal section of the machine, and Fig. 2 is a cross-section at the line *xx*.

The shaft *a* has across its end a groove or mortise, into which are received the dies *c c*, in which are the semicircular grooves for the swaging of the needle-blank or other article—such as a rod, shaft, or bar—and the cap-plate *f* is fastened to the end of the shaft by screws, and it is provided with the adjusting-screws *i*, that enter holes in the dies to regulate the ex-

tent of opening of the dies, substantially the same as in the said Patent No. 58,730. I remark that, if desired, the shaft *a* may be tubular for the passage of the wire, rod, shaft, or bar that is operated on, and the parts may be of any desired size. If the shaft *a* is revolved by the pulley *k* or otherwise, the article to be acted upon will only require to be fed in gradually and be free to be revolved by the action of the dies as they move slightly while grasping such article; or if the article is revolved automatically the dies and shaft *a* may remain stationary while the shell *b* is revolved by power. This shell *b* is made as a cylinder, and between its inner surface and the shaft *a* there is a circular range of cylindrical rollers, *l*, the axes of which are supported by and revolve in the ring-bearings *n n*. There are eight of these rollers shown. The number may be more or less. The rollers roll upon the interior surface of the shell *b*, and the ends of the dies *c*, as they are revolved, come into contact with the rollers in succession and act to turn such rollers progressively, and each roller forms a toggle between the interior surface of the shell and the end of the die, and the die is closed to the full extent when the center of the die is in a radial plane passing through the axis of the roller with which such die is in contact.

I have shown in Fig. 3 an elevation of a complete set of dies of larger size. I prefer to make these dies double—that is, with a die-face at each end of the blocks of metal *c c*—and there are followers *o o*, against the rounded exterior of which the rollers *l* act in the swaging operation. When the die-faces in the center are worn they are resurfaced and rebored, and it becomes necessary to use filling-pieces *r* to compensate for the metal removed, and I use any thickness or number of filling-pieces required. The die-blocks having faces at both ends allows of their being turned end for end and used for a longer period without requiring to be resurfaced and bored. The dies and rollers do not slide one on the other, but the contact is a rolling movement. Hence there is but little friction, and the power is expended to the best advantage in compressing the article that is placed between the dies, thereby cold-swaging the same, so as to reduce a wire to a needle-blank, or to straighten or point

wires or rods, or to straighten and render uniform in size rods or shafts. I remark that where two dies are used there must be an even number of rollers, so that they act at opposite 5 sides of the circular shell. If there are three dies *c* placed radially at equal distances apart of one hundred and twenty degrees, there must be six, nine, or twelve rollers.

I claim as my invention—

10 1. The combination, with the dies *c* and shaft *a*, of the cylindrical shell *b* and circular range of rollers, substantially as set forth.

2. The combination, with the dies *c* and shaft *a*, of a cylindrical shell, *b*, rollers *l*, and ring-bearings *n* for the axes of the rollers, substantially as set forth. 15

Signed by me this 14th day of March, A. D. 1882.

WILLIAM H. DAYTON.
